FIRE ESCAPE.

No. 394,625.

Patented Dec. 18, 1888.

UNITED STATES PATENT OFFICE.

WILLIAM H. WELLS, OF CHRISMAN, ILLINOIS, ASSIGNOR OF ONE-THIRD TO
CHARLES L. KENTON, OF SAME PLACE.

FIRE-ESCAPE.

SPECIFICATION forming part of Letters Patent No. 394,625, dated December 18, 1888.

Application filed May 8, 1888. Serial No. 273,223. (No model.)

To all whom it may concern:

Be it known that I, WILLIAM H. WELLS, a citizen of the United States, residing at Chrisman, in the county of Edgar and State of Illinois, have invented new and useful Improvements in Fire-Escapes, of which the following is a specification.

My invention relates to improvements in fire-escapes; and it consists in the peculiar construction and combination of devices, that will be more fully set forth hereinafter, and particularly pointed out in the claims.

The object of my invention is to provide a fire-escape which is arranged on a truck that is adapted to be readily transported through the streets of the city or town, and is adapted to be extended vertically to any desired height and inclined toward the burning building, so as to form a descent-ladder to facilitate the escape of the inmates; and a further object of my invention is to provide means for lowering timid and helpless persons from the windows of a burning building without injury. These objects I attain by the mechanism illustrated in the accompanying drawings, in which—

Figure 1 is partly an elevation and partly a vertical sectional view of a fire-escape embodying my improvement when the same is extended to its full height. Fig. 2 is a similar view showing the fire-escape lowered. Fig. 3 is a vertical sectional view taken on the line $\alpha\alpha$ of Fig. 2. Fig. 4 is an end elevation of my improved fire-escape.

A represents a rectangular horizontal base-frame, which is supported on a front axle, B, and a rear axle, C. The said axles are each provided with supporting wheels or rollers D, by means of which the fire-escape may be readily drawn through the streets. From the side beams of the frame A, and near the corners thereof, project four vertical corner-posts, E, inclosing a rectangle, the sides of which are formed by horizontal rungs F, which connect the posts E in pairs, as shown. On the inner corners of the said posts are secured vertical guides G. The posts E and the rungs F form the lower or base section of the escape.

H represents a similarly-constructed section, which is somewhat smaller than the

lower section and is arranged within the same and guided vertically by the guides G. Across the bottom of the section H extends a pair of bars, I, which are arranged on the outer side of a pair of vertical standards, K, which project from the center of the bottom of the base-section and are provided at their upper ends with pulleys L.

M represents a shaft, which extends longitudinally through the frame A, in the center of the same, and has its bearings in the cross-beams at the ends of said frame. Secured rigidly to the said shaft near one end thereof and bearing against the inner side of one of the cross-beams of the frame is a ratchet-wheel, N.

O represents a gravity-pawl, which is pivoted to the said cross-beams and normally engages the teeth of the said ratchet-wheel. Near one end of the shaft M and bearing against the front end of the frame A is secured a friction-wheel, P.

R represents a lever, which is pivoted at its lower end to the cross-beam at the frame A, and S represents a friction-strap which has one end rigidly secured to the said cross-beam, is then passed around the friction-wheel P, and has its opposite end secured to the lever R.

Suitable cranks, T, are attached to the ends of the shaft M, by means of which the latter may be rotated, as will be readily understood.

U represents a pair of ropes which have their lower ends attached to the central portion of the shaft M, and are then passed upward on the inner sides of the standards K, over the pulley L, and have their upper ends rigidly secured to the bars I at the base of the section H. The latter section has anti-friction rollers V, journaled on the upper rungs of opposite sides thereof.

W represents a pair of ropes which have their lower ends attached to the lower sides of the base-section and have their upper ends attached to the lower sides of the section H, the function of the said ropes being to limit the upward movement of the section H in the base-section.

X represents a section which is similar in construction to the section H, somewhat

smaller than the same, and is arranged and guided in suitable corner guides, Y, with which section H is provided. The section X has ropes Z attached to its lower side, passed 5 over the rollers V, and attached to the upper sides of the base-section. A further series of similarly-constructed sections are nested one within the other and arranged in the section H and adapted to telescope, each interior 10 section having its lower sides connected to the upper sides of one of the outer sections by ropes similar to the ropes Z, which pass over rollers that are similar to the rollers V. To the extreme upper end of the inner or upper 15 per section is pivoted a crane or arm, B', which has a block or pulley, C', at its outer end, and suitable guy-ropes, D', are attached to the said crane or arm, whereby the latter may be swung in any desired direction. Attached 20 to the telescopic sections of the escape at suitable points are a series of ropes, E', which are provided at their lower ends with hooks or rings F', which are adapted to be readily grasped by the hands.

25 G' represents an elevating-rope, which is attached at one end to a suitable winch or windlass, H', secured on the base-frame, and the said rope is passed through the pulley C' of the crane-arm B', and has a suitable basket 30 or sling, I', attached to its lower end. The said rope is of sufficient length to extend to the crane-arm at the top of the escape, and from thence downward to the ground when the escape is extended to its full height.

35 The cross-beams at the ends of the base-frame are each secured to one of the axles near one end by a hinged plate, L', and are each secured to the opposite end of one of the axles by a plate, M', having a vertical slot, 40 N', in its upper end. Bolts O' work in the said slots and engage the end beams of the base-frame. Said end beams of the base-frame are further connected to the axles by means of vertical bolt-rods P', which extend 45 through them and through the axle and have the clamping-nuts R' at their upper end. The side beams of the base-frame, which are arranged in proximity to the plates M', are provided with elevating-screws S', the lower ends 50 of which are adapted to bear on the axles.

55 The operation of my invention is as follows: The fire-escape is in its initial position when all of the sections are lowered and nested one within the other. When thus arranged, the fire-escape may be readily drawn to a burning building, and when arranged in front of the same and at a suitable distance therefrom the shaft M is rotated in the direction of the arrow in Fig. 4. The shaft is rotated 60 by a number of men, who grasp the cranks at the ends of the shaft. As the said shaft rotates, it winds up the ropes U, and thereby causes the section H to be raised in the base-section, and each succeeding inner section is raised in its fellow outer section by means of the ropes Z, as will be readily understood, so that all

the sections of the fire-escape are extended vertically until the upper end of the fire-escape is at a sufficient height from the ground, according to the height of the burning building. The pawl by engaging the ratchet-wheel prevents retrograde rotation of the drum-shaft M, and consequently prevents the sections of the fire-escape from collapsing. Having thus erected the fire-escape, the nuts R' 70 on the bolts P' are loosened and the screws S' are turned, so as to cause the base-frame to tilt or incline to one side on its supporting-axles, the plates L' forming the pivots or hinges on which the base-frame turns and the slots 80 in the plates M' serving to limit the inclination of the base-frame. By thus inclining the base-frame the fire-escape is inclined toward the burning building, as will be very readily understood, thus causing the depending ropes 85 attached to the sections of the fire-escape to swing against the wall of the building, where they may be readily grasped by persons in the windows of the building, who by means of them swing themselves from the building 90 to the escape, and then descend the ladder on the side rungs thereof.

95 By reason of the guide-ropes the crane or arm may be swung in any direction, so as to direct the sling or basket, when the ladder is raised, to any window or balcony of the building, from which persons who are unable to descend by the escape may step into the basket or sling and be safely lowered to the ground.

100 In order to lower the fire-escape, so as to restore the same to its normal collapsed condition, a number of men grasp the lever R, so as to cause the strap S to be tightened sufficiently on the friction-wheel P. The pawl is 105 then disengaged from the ratchet, and the shaft is caused to turn slowly in a retrograde direction, so as to uncoil the ropes U, and thereby permit the sections of the escape to slowly descend.

110 By adding a sufficient number of sections to the escape the latter may be adapted to be raised to the top of a building of any height.

115 I am aware that it has been heretofore proposed to provide a fire-escape with telescopic nested sections, elevating-ropes connecting the same together in pairs, pulleys or guides therefor, and a winch and ropes attached thereto, passed over guides or pulleys, and secured to the lowermost movable section, and this, broadly, I disclaim.

120 Having thus described my invention, I claim—

1. The combination, in a fire-escape, of the nested sections having the side rungs, the elevating-ropes connecting the same together in pairs and passing over suitable rollers or guides, and the shaft and elevating-ropes attached thereto, guided over suitable pulleys, and secured to the lowermost movable section, whereby the sections may be extended or retracted telescopically, and the ropes W, 125 130

connecting the base-section and the lower-most movable section, substantially as described.

2. The fire-escape having the nested telescoping sections and the crane or arm pivotally attached to the upper end of the uppermost section and adapted to be swung in a horizontal plane, the guy-ropes attached to the crane, and the hoist suspended from the 10 said crane-arm, substantially as described.

3. The combination of the supporting-axles, the base-frame secured to and adapted to be tilted thereon, the telescoping sections supported on the base-frame, and the screws S', 15 engaging the base-frame and bearing on the axles, whereby the base-frame may be tilted, substantially as described.

4. The combination, in a fire-escape, of the base-frame supporting the nested sections, 20 the supporting-axles arranged under the base-frame, the bolts extending through the base-frame and through the said axles and having

the adjustable clamping-nuts, and the set-screws for raising and lowering one side of the base-frame when the clamping-nuts are 25 loosened, substantially as described.

5. The combination, in a fire-escape, of the base-frame supporting the nested sections, the supporting-axles arranged under the base-frame, the hinge-plates L', connecting said 30 base-section at one side to the axle, the slotted plates M', extending from the axles near their opposite ends, and the bolt projecting from the base-sections and working in the slots of the said plates, substantially as described. 35

In testimony that I claim the foregoing as my own I have hereto affixed my signature in presence of two witnesses.

WILLIAM H. WELLS.
